UNITED STATES PATENT OFFICE.

GEORGE H. NORTH, OF KANSAS CITY, MISSOURI.

VALVE-RESEATING TOOL.

Application filed August 15, 1924. Serial No. 732,210.

To all whom it may concern:

Be it known that I, GEORGE H. NORTH, a citizen of the United States, residing at Kansas City, in the county of Jackson and 5 State of Missouri, have invented new and useful Improvements in Valve-Reseating Tools, of which the following is a specification.

This invention relates to tools intended for 10 use by automobile mechanics and others, and has for its object the provision of a novel tool which is particularly well adapted for reaming out, enlarging or refacing valve seats or openings in internal combustion engines and the like.

An important object is the provision of a tool of this character which is fully adjustable whereby not only to act upon valve openings or seats of different sizes, but also 20 to act selectively on the valve openings and the seat separately whereby the area of the seat may be made greater or less, depending upon circumstances or the wishes of the operator.

25 Another object is the provision of a tool of this character which is provided with removable guide elements the intention being that a plurality of these guide elements be provided, a selected one of which may be used depending upon the size of the valve stem guide in the motor worked upon.

Yet another object is the provision of a tool of this character which will be simple and inexpensive in manufacture, easy to 35 adjust and use, positive in action, durable in service, and a general improvement in the art.

With the above and other objects and advantages in view, the invention consists in 40 the details of construction, to be hereinafter more fully described, and claimed, and illustrated in the accompanying drawings, in which:

Figure 1 is a side elevation of the tool 45 showing it in the act of reaming out a valve opening in an engine, a portion of the engine being represented in section.

Figure 2 is a view partly in elevation and partly in sections showing the body of the 50 device.

Figure 3 is an end elevation looking toward the cutter blade.

Figure 4 is a view similar to Figure 1 55 but showing the tool in the act of working upon the valve seat.

Figure 5 is a detail view of the device showing the nut member in section.

Figure 6 and 7 are detail views showing different sizes of guide elements and

Figure 8 is a detail perspective view of 60 one of the blades.

Referring more particularly to the drawings, the letter A designates a portion of an engine having a valve opening therein which it is desired to dress out or ream. As is 65 well known, a valve opening of this type has two portions, one portion B constituting the opening proper and the other portion C constituting the seat for the valve which is used in connection therewith. Quite naturally, it may be necessary only to reface or dress the seat itself whereas in some cases it is really necessary to ream out the hole itself, this detail depending upon the nature of the work to be done. 70

In carrying out the invention, I provide an elongated stem or body member 10 which includes a threaded intermediate portion 11 and an unthreaded shank portion 12 terminating in a reduced threaded extension 13 upon which is mounted a handle 14 of suitable size and shape. At the end opposite the handle the body 10 is somewhat enlarged and formed with a plurality of pairs of ears 15 and a centrally arranged threaded socket 16. The pairs of ears are provided with alining apertures 17. 75

Pivoted between the pairs of ears are blades 18 held in place by means of screws or bolts 19 which pass through the blades 90 and through the alining or registering holes 17 in the ears 15. These blades are normally urged upwardly and toward each other by means of coil springs 20 which might be connected with the successive blades but which are here represented as passing through holes 21 formed in the blades. In this way it is quite obvious that 95

a single ring-like spring member may be provided instead of a plurality. However, it should be understood that there is absolutely no limitation as to this detail as it is obvious that any other elastic or spring means might be provided for urging these blades in an upwardly extending direction. The outer edges 22 of the blades are sharpened so that they will be capable of having a cutting effect upon the metal at the opening B or at the seat C depending upon circumstances. 100 105 110

In order that the blade members may be moved and held in any desired adjusted position, I make use of a shell member 23 which has a central hub 24 formed with a threaded bore screwed into the threaded intermediate portion 11 of the body. This shell member is of such diameter that the edge thereof will engage upon the upper edges of the blades 18 for moving the blades 10 as may be desired. Threaded upon the intermediate portion 11 of the body is an adjusting nut 25 which engages against the shell 23 and which is operable to move the shell longitudinally with respect to the body 15 for varying the position of the blades.

Quite naturally, it is imperative that guide means be provided for centering the device properly with respect to the hole to be dressed out or reamed. In carrying out 20 this feature I make use of an elongated stem 26 which is formed with a threaded end detachably engaged within the screw threaded socket 16 above referred to. It is true that in some instances, the valve guide D in the 25 motor is not of the same diameter or in other words it should be stated that in some motors the guide has a greater diameter than in others. To take care of this, it is contemplated that a plurality of such guide 30 stems be provided, any one of which may be used in connection with the tool depending upon the size of the openings through the valve guide. In Figure 7 I have shown a stem 27 which is of larger diameter than the stem 26 but formed with a reduced 35 threaded extension 28 which will act exactly the same as the threaded end of the stem 26. Regardless of the size of the guide stem employed, it is evident that the stem is 40 screwed into the socket 16 so that it may subsequently be slipped through the valve guide D to form a centering device for the tool.

In the operation, it is apparent that after 45 the tool is placed in position the nut 25 is adjusted so that the shell is moved in such a way as to bring the blades 18 to the desired position depending upon the size of the hole worked upon. If it is the portion 50 B of the hole which is to be reamed out, it is evident that the blades may be permitted to extend upwardly at a more acute angle

than if it is the seat portion D which is to be reamed or dressed. The two different positions and actions are illustrated in 55 Figures 1 and 4 respectively.

Assuming that all necessary adjustments have been made, it is quite apparent that when the operator grasps the handle 14 and rotates the tool, the edges 22 of the blades 60 act to ream the metal at the hole portion B or C as the case may be and either enlarge the hole or reface the valve seat depending upon what is desired.

From the foregoing description and a 65 study of the drawings it will be apparent that I have thus provided a simply constructed, inexpensive and very easily adjusted and operated tool for the purpose specified, which will efficiently perform all 70 the functions for which it is intended. Owing to the simplicity of the construction, it is readily apparent that there is very little 75 to get out of order and that the device should have a long and satisfactory life.

While I have shown and described the preferred embodiment of the invention, it should be understood that I reserve the right to make such changes in the form, 80 construction and arrangement of parts as will not depart from the spirit of the invention or the scope of the subjoined claim.

Having thus described the invention, I claim:—

A tool of the character described comprising an elongated body member having a threaded intermediate portion, a handle mounted upon one end of said body, the other end of the body being formed with a plurality of spaced ears, blades pivoted between said spaced ears and having their outer edges sharpened, spring means engaging said blades normally urging them in one direction, a shell member slidably engaged upon the body and engageable with 90 said blades whereby to move the same into adjusting position, and a nut member 95 screwed upon the threaded intermediate portion of the body and engaging said shell for moving the same.

In testimony whereof I affix my signature.

GEORGE H. NORTH.
